US0D1107754S

(12) **United States Design Patent** (10) **Patent No.:** **US D1,107,754 S**
(45) **Date of Patent:** **** Dec. 30, 2025**

(54) **DISPLAY SCREEN OR PORTION THEREOF
WITH GRAPHICAL USER INTERFACE**

(71) Applicant: **Panasonic Intellectual Property Management Co., Ltd.**, Kadoma (JP)
(72) Inventor: **Takuya Yanaga**, Tokyo (JP)
(73) Assignee: **PANASONIC INTELLECTUAL PROPERTY MANAGEMENT CO., LTD.**, Osaka (JP)

(**) Term: **15 Years**

(21) Appl. No.: **29/989,360**

(22) Filed: **Feb. 12, 2025**

(30) **Foreign Application Priority Data**

Oct. 23, 2024 (JP) ..... 2024-021980 D

(51) **LOC (15) Cl.** **14-04**

(52) **U.S. Cl.**
USPC **D14/492**; D14/489

(74) *Attorney, Agent, or Firm* — WHDA, LLP

(57) **CLAIM**

The ornamental design for a display screen or portion thereof with graphical user interface, as shown and described.

DESCRIPTION

The single FIGURE is a front view of a display screen or portion thereof with graphical user interface showing my new design.

The broken lines in the drawing illustrate portions of the display screen or portion thereof with graphical user interface that form no part of the claimed design.

1 Claim, 1 Drawing Sheet
